UNITED STATES PATENT OFFICE.

PHARES M. MISHLER, OF HAGERSTOWN, MARYLAND.

PORTABLE FENCE.

SPECIFICATION forming part of Letters Patent No. 397,511, dated February 12, 1889.

Application filed November 12, 1888. Serial No. 290,592. (No model.)

To all whom it may concern:

Be it known that I, PHARES M. MISHLER, a citizen of the United States, residing at Hagerstown, in the county of Washington and State of Maryland, have invented certain new and useful Improvements in Portable Fences; and I do hereby declare the following to be a full, clear, and exact description of the invention, such as will enable others skilled in the art to which it appertains to make and use the same.

This invention relates to certain novel improvements in portable fences; and it has for its objects to connect the palings constituting the body of the fence to each other and to the uprights or posts in a convenient and substantial manner; and it further consists in providing said portable fence with a post composed of three parts having pivotal connections, whereby said post can be readily folded, so that the fence may be easily and quickly put up and taken down and removed or changed from place to place, as will be hereinafter more fully explained.

Figure 1 is a side view of my fence. Fig. 2 is a vertical cross-section of the same. Fig. 3 is a detail view of the end fastenings in modified form. Fig. 4 is a detail view of the rail-wire in modified form, and Fig. 5 is a detail view of the upper or lower rail.

Referring by letter to the accompanying drawings, A designates the uprights or fence-posts, consisting of the vertical portion a , the inclined bar a' , and the transverse sill a'' , all of which have a pivotal connection to one another. The inclined bar a' is pivoted at a^3 to the upright a , and the transverse bar or sill is pivoted at a^4 to the lower portion of said vertical portion a . The lower end of the inclined bar is provided with a perforation, b , and the sill has perforations $b' b' b''$, and through which and the perforation in the inclined bar is passed a pin, b^3 . On the face of the vertical bars a , and between the same and the palings, is arranged a vertical wire, b^3 , which is secured to said bar at the top by a staple, b^4 , while the points thereof at the bottom are bent and driven into the bar, as shown at a^4 in the drawings. This wire is a continuous piece and bent in U-shaped form and serves to separate the palings from the post, whereby

they do not come in contact with one another, thus avoiding decay of the wood.

The letters B B indicate twin upper and lower rails for the fence. The same consists of a strong wire bar, which is bent transversely at intervals, forming a shoulder, c , at each end of the depression c' and horizontal face portion c'' . The wire rails are provided at one end with an eye, c^3 , and at the opposite end with hooked or projecting portion c^4 , which is bent as shown, and provided with screw-threads to receive a nut, whereby the sections of the fence are coupled together.

C C represent a series of parallel inclined palings, which are placed within the depressions of the upper and lower horizontal wire rails, which latter form a continuous strand embracing each section of the fence.

D indicates a wire, one end of which is secured to the end of the wire rail and wound about the said rail its entire length and on opposite sides of the palings, as shown in Fig. 1 of the drawings, thereby forming, in connection with the wire rail, a loop, d , in which are embraced palings, both at the top and bottom thereof, thus holding them in position.

To strengthen and further brace my fence, I provide an additional diagonal wire connection for each panel of a fence by means of a continuous wire, E, which passes diagonally down from the top of the section, where it is looped around the top rail and first paling, then extending downwardly to the lower end of the paling at the opposite end of the section, and the said wire is looped around each paling, as shown, at equidistant intervals. The vertical post aforesaid is secured to the panel of the fence by a wire, d' , wound around the paling and post in serpentine form, thus binding the two parts together. The lower end of this serpentine wire has a loop, d^3 , at its lower end, in which may be driven a stake for more securely holding the fence to the ground.

It will be observed that the post of the fence can be readily folded by simply withdrawing the pin, thereby freeing the base from the inclined bar, when the two latter can be turned on their pivots, thus folding said post, and will be found convenient for shipping as well as for moving the fence from place to place, and it is durable and cheap to build. Instead

of the bent rail, as described, I may use a **V**-shaped bend for the palings.

It is obvious that many ways are convenient for coupling the sections together. For 5 instance, a common loop may be employed, or a key-hole-shaped loop and a **T**-shaped head, as shown in the drawings, as well as that shown with screw hook and nut. However, I do not confine myself to any precise fastening 10 for the sections of the fence, as various means may be employed without departing from the spirit of my invention.

It will be further seen that by providing the 15 base-bar with two or more perforations the inclined bar can be adjusted in such a manner that the fence can be made to accommodate itself to uneven ground—as the side of a hill—by withdrawing the holding-pin and setting it in either of the perforations, as may 20 be desired in giving the fence a vertical position.

What I claim, and desire to secure by Letters Patent, is—

The within-described portable fence, consisting of the post composed of three parts— 25 to wit, the vertical portion, inclined bar, and base—all pivoted to one another and capable of being folded, as described, the upper and lower rails having depressions, the palings secured in these depressions by the tie-wire 30 wound around them, the diagonal brace-wire, the wire shield on the face of the post, and the serpentine wire having loops at its lower end to receive a stake, the whole arranged substantially as described. 35

In testimony whereof I affix my signature in presence of two witnesses.

PIARES M. MISHLER.
